[57] CLAIM

The ornamental design for a cap, as shown and described.

DESCRIPTION

FIG. 1 is a front perspective view of a cap showing my new design;

FIG. 2 is a front elevation view of the cap of FIG. 1;

FIG. 3 is a right side elevation view of the cap of FIG. 2;

FIG. 4 is a rear elevation view of the cap of FIG. 2;

FIG. 5 is a left side elevation view of the cap of FIG. 2;

FIG. 6 is a top plan view of the cap of FIG. 2;

FIG. 7 is a bottom plan view of the cap of FIG. 2;

FIG. 8 is a front elevational view of a second embodiment of a cap showing my new design;

FIG. 9 is a rear elevation view of the cap of FIG. 8;

FIG. 10 is a front elevational view of a third embodiment of a cap showing my new design;

FIG. 11 is a rear elevation view of the cap of FIG. 10;

FIG. 12 is a front elevational view of a fourth embodiment of a cap showing my new design;

FIG. 13 is a rear elevation view of the cap of FIG. 12;

FIG. 14 is a front elevational view of a fifth embodiment of a cap showing my new design;

FIG. 15 is a rear elevation view of the cap of FIG. 14;

FIG. 16 is a front elevational view of a sixth embodiment of a cap showing my new design;

FIG. 17 is a rear elevation view of the cap of FIG. 16;

FIG. 18 is a front elevational view of a seventh embodiment of a cap showing my new design;

FIG. 19 is a rear elevation view of the cap of FIG. 18;

FIG. 20 is a front elevational view of an eighth embodiment of a cap showing my new design;

FIG. 21 is a rear elevation view of the cap of FIG. 20;

FIG. 22 is a front elevational view of a ninth embodiment of a cap showing my new design;

FIG. 23 is a rear elevation view of the cap of FIG. 22;

FIG. 24 is a front elevational view of a tenth embodiment of a cap showing my new design; and,

FIG. 25 is a rear elevation view of the cap of FIG. 24.

The broken line showing of word and number “Logo 1” in FIGS. 1 through 6 is for illustrative purposes only and forms no part of the claimed design.
